UNITED STATES PATENT OFFICE.

MORITZ KRICKL, OF NEW YORK, N. Y.

DESIGN FOR STAIR-RODS.

Specification forming part of Design No. **11,190**, dated May 13, 1879; application filed April 15, 1879.
[Term of patent 7 years.]

To all whom it may concern:

Be it known that I, MORITZ KRICKL, of the city, county, and State of New York, have invented a new and original Design for Stair-Rods, of which the following is a full, clear, and exact description, reference being had to the accompanying drawings, making part of this specification, and in which—

Figure 1 represents a perspective view of my improved stair-rod, and Fig. 2 a vertical transverse section of the same.

Similar letters of reference indicate the same parts.

This invention relates to an improved design for stair-rods; and consists of a stair-rod of square cross-section, having one or more concave sides.

Referring to the drawings, A represents a stair-rod of square cross-section, the sides a

of which, either one, two, or all, are concaved, so that a lighter and more ornamental character is thereby imparted to the stair-rod, in place of the heavy and somewhat clumsy appearance of the plain square rod.

Having thus described my invention, I claim as new and desire to protect by Letters Patent—

The design for a stair-rod, consisting of a rod of square cross section, and with one or more concave sides, as shown and described.

In testimony that I claim the foregoing as my invention I have signed it this 12th day of April, 1879.

MORITZ KRICKL.
